UNITED STATES PATENT OFFICE

2,529,074

WOMAN'S HOSE SUPPORTER

Lenore B. Cooley, New York, N. Y.

Application November 23, 1946, Serial No. 711,859

3 Claims. (Cl. 2—33)

1

This invention relates to hose supporting means for women.

The usual hose supporting means for women as, for example, the conventional garter belt, is objectionable because of its tendency to crawl below the waistline, with considerable discomfort to the wearer.

One object of the invention is a hose supporting means or device in which the above noted objections or disadvantages and others of conventional supporters are obviated.

A further object of the invention is a novel and improved garter belt which is characterized by its simplicity in design, the ease and comfort with which it may be worn and the economy with which it may be manufactured.

Further objects of the invention will herein-after appear.

For a better understanding of the invention reference may be had to the accompanying drawings forming a part of this application, wherein

Fig. 1 is an elevational view of a garter belt embodying the invention;

Figs. 2A and 2B are plan views of parts of the belt of Fig. 1 before assembly;

Fig. 3 is a plan view of the parts shown in Figs. 2A and 2B assembled and fastened together;

Fig. 4 is a bottom view of the partially completed garment shown in Fig. 3 illustrating the completion of the garment;

Fig. 5c is a diagrammatic view simulating a sectional view along the line 5c—5c of Fig. 1;

Fig. 6 is a sectional view along the line 6—6 of Fig. 1; and

Fig. 7 is an elevational view of a modification of the garment.

Referring to Figs. 1 to 6, I have illustrated the invention as embodied in a garter belt designated by the numeral 1. The belt embodies a part A above the waistline 2 and a part B below the waistline 2. The part B has attached thereto or formed therewith the hose supporter straps 3 and garters 3' of conventional character are attached to the straps. The lower part B of the belt in addition to functioning as a means for attaching the garters 3', is designed to make a form fit about the hips of the wearer. The upper part A of the belt is of frusto-conical shape, flaring outwardly in an upward direction from the narrow waistline 2. The frusto-conical part A is self-sustaining but is laterally flexible and yielding to accommodate itself to the body portion just above the waistline without binding in any body position. It is of shallow depth and

2

I have found a depth of around two inches quite satisfactory, though fairly satisfactory results may be obtained with depths of up to 2½ inches and down to 1½ inches. The lower part B of the belt is preferably of greater depth than the depth of the part A and in the particular embodiment shown in Fig. 1 the depth of the part B is equal to or slightly greater than twice the depth of the part A although this relationship in depth may be varied.

The upper part A of the garment is formed of the strip shown in Fig. 2A. It comprises a multiplicity of panels 6 of the required depth which are sewed together along the lines 7. These panels 6 are slightly tapered from their upper edges 8 to their lower edges 9 so as to form a strip when the panels 6 are sewn along the lines 7 of arch shape illustrated in the drawing. The part B of the garment is formed of a strip illustrated in Fig. 2B. This strip is also formed of a multiplicity of panels, these panels being designated 6' and these panels of which the strip of Fig. 2B is formed are also tapered, in this case being tapered from the lower edge 8' to the upper edges 9'. Like the panels of the strip of Fig. 2A the panels of Fig. 2B are sewn together along their tapered edges to form the seams 7'. An arcuate strip B is thus formed which is generally similar to the arcuate strip of Fig. 2A. These two strips A and B are sewn together along their inner arcuate edges 9 and 9' respectively to form the waistline 2, the garment in this stage being illustrated in Fig. 3.

The parts A and B of the garment may be made of similar or different fabric materials but preferably of the same material as, for example, rayon silk and other conventional materials. If the material is heavy enough the upper part A of the garment may have sufficient self-sustaining character as to render unnecessary any added stiffening means. When the fabric of which the garment is made is of medium or light weight material it may be desirable to incorporate some additional stiffening means and Fig. 4 illustrates this added stiffening means as being in the form of a pair of spaced stays 10, these stays being of any conventional material which though laterally flexible imparts to the upper part A of the garment greater stiffness. They are enclosed in envelopes 11 sewn on to the inner side of the garment along one of the seams 7, 7'.

The belt is formed as described of a multiplicity of tapered panels 6, 6' and in the particular embodiment shown there are eight of such panels

in each part A and B and I have found that number of panels as particularly suitable for a belt of medium sized girth. The panels 6, 6' are sewn together to form the garter belt 1 having the lower form fitting part B and the upper self-sustaining frusto-conical part A just above the waistline 2 as described above. Preferably the panels are sewn together first to form the separate arcuate strips A and B of Figs. 2A and 2B and then the strips are sewn together along their shorter arcuate edges 9, 9' to form the belt 1. The outer edges 20, 21 of the outer panels are provided with suitable complementary fastening means 22, 22' for fastening the belt 1 about the waist.

In the embodiment of Fig. 7 the lower part B' of the garter belt is of shorter depth than the similar part B of Fig. 1 while the upper part A' is roughly the same depth as that of part A. Otherwise the embodiment of Fig. 7 is like that of Fig. 1.

I have found that the garter belt of this invention has a very substantially less tendency to slip below the waistline than the conventional garter belt or similar conventional hose supporter. It tends to cling to the waistline and not to crawl under the more or less muscular abdomen structure, or it tends to prevent the latter from rolling or crawling over the waistline of the belt, in contrast with conventional belts which often cause considerable discomfort due to an opposite tendency. I believe this functioning of my garter belt is due to the upstanding frusto-conical part A of shallow depth extending from a narrow waistline 2 (in the particular embodiment shown being the depth of the seam 9-9') and snugly but yieldingly fitting the wearer just above the waist line, without binding and pressing. The main body part of the belt may be made of any suitable fabric material such for example as the inelastic cotton, rayon, nylon or silk materials, although some elasticity may be incorporated if desired.

I claim:

1. A garter belt for women comprising upper and lower sections, said upper section being arcuate in shape and having substantially parallel

edges when freely extended to lie in a plane, the lower section having a generally arcuate shape when freely extended to lie in a plane, the upper edge of said lower section being curved oppositely to the edges of said upper section, said lower section having garters thereon at spaced points, the lower edge of said upper section being joined to the upper edge of said lower section whereby to provide a waistline for said garter belt, the arcuate shapes of said joined parts causing said garter belt snugly to fit a wearer in a form fitting manner above and below the waist.

2. The garter belt of claim 1 including a pair of vertical stays circumferentially spaced from each other and extending above and below the waistline.

3. A garter belt for women comprising a plurality of vertical panels of relatively inelastic fabric material, each panel consisting of an upper garter belt part and a lower garter belt part, the upper part of each of said panels tapering from the top of said garter belt downwardly, the lower part of each of said panels tapering upwardly from the lower part of said garter belt, a pair of adjoining lower garter belt parts having garter connections, a second pair of lower garter belt parts having garter connections, each part of said second pair flanking said first pair with at least one panel part interposed between, and means for joining the ends of said garter belt when it is positioned around the body of a wearer.

LENORE B. COOLEY.
